Primary Examiner — Rashida Johnson(74) *Attorney, Agent, or Firm* — Banner & Witcoff, Ltd.(57) **CLAIM**

The ornamental design for shorts, as shown and described.

DESCRIPTION

FIG. 1 is a right front perspective view of the shorts showing our new design in an in-use configuration;

FIG. 2 is a rear perspective view thereof;

FIG. 3 is a front view thereof;

FIG. 4 is a rear view thereof;

FIG. 5 is a right side view thereof; and,

FIG. 6 is a left side view thereof.

The broken lines immediately adjacent to the shaded area represent unclaimed boundaries of the design. The unshaded regions of the shorts, demarcated by broken lines, are for environmental purposes only and form no part of the claimed design. The contrast shading represents a contrast in appearance only and does not represent any particular color, material, texture or finish.
